(57) **CLAIM**

The ornamental design for a safety stanchion and belt reel, as shown and described.

DESCRIPTION

FIG. 1 sets forth a perspective view of a safety stanchion and belt reel showing the present invention new design;

FIG. 2 is a right side view thereof;

FIG. 3 is a left side view thereof;

FIG. 4 is a front view thereof;

FIG. 5 is a rear view thereof;

FIG. 6 is a top view thereof;

FIG. 7 is a section view thereof taken along section lines 7-7 in FIG. 1; and,

FIG. 8 is a bottom view thereof.

The broken lines throughout the figure views depict portions of the safety stanchion and belt reel that form no part of the claimed design.
